UNITED STATES PATENT OFFICE.

PETER TAYLOR, OF GLASGOW, SCOTLAND, ASSIGNOR TO THE SINGER MANUFACTURING COMPANY, OF ELIZABETH, NEW JERSEY, A CORPORATION OF NEW JERSEY.

SEWING-MACHINE CABINET.

Application filed November 10, 1925, Serial No. 68,063, and in Great Britain June 19, 1925.

This invention relates to devices for initially raising panels or covers affording no convenient finger grip, so that such covers may be readily grasped by hand and opened. 5 For example, sewing machine cabinets are customarily constructed in the form of a library table, the top of which is formed with a rectangular aperture to receive the sewing machine; the latter being adapted to 10 be dropped or swung through such aperture into a cavity or receptacle below the table-top, when not in use. The table-top commonly includes an in-set hinged panel or cover, preferably formed in hinged sections, 15 which serves to close the aperture in the table-top when the machine is lowered; the panel or cover being then flush with the remainder of the table-top.

With a cabinet or other receptacle having 20 a cover of this nature, it is difficult to catch hold of the cover to raise the same. A finger grip set flush with the upper side of the cover has been proposed but such a device is conspicuous and mars the appearance of 25 the table-top as a whole. Further, such finger grip is difficult to grasp securely and is likely to cause injury to the finger nails of the user.

The present invention has for an object 30 to provide a concealed and easily operated device for initially raising a cover so that it may be readily grasped and opened by the user.

To the attainment of the ends in view 35 there is provided a device, preferably in the form of a push-rod, located at the side of the receptacle and extending into the latter, such rod having means at its inner end adapted to engage and lift the cover. Preferably, 40 the rod is formed at its inner end with an inclined cam edge which engages and lifts the cover when the rod is pushed inwardly. A spring restores the rod to initial position, entirely at one side of the aperture closed 45 by the cover, when the latter is released by the operator.

In the drawings, Fig. 1 is a top plan view 50 of a sewing machine cabinet of the library table type embodying the invention. Fig. 2 is a section on the line 2-2, Fig. 1. Fig. 3 is a sectional view on the line 3-3, Fig. 1. Fig. 4 is a similar view showing the cover lifting rod projected into lifting engagement

with the cover member of the cabinet and Figs. 5 and 6 are detail perspective views of 55 the guide and rod members shown in Figs. 3 and 4.

The invention is shown as embodied in a sewing machine cabinet comprising a table-top 1 supported by the legs 2 and connecting 60 side wall members 3 defining a receptacle or cavity for the usual sewing machine 4.

The top wall of the table is formed with an aperture which is closed by means of the in-set flush panel or cover 5 hinged at 6 to the table-top 1. This cover is preferably made in three sections 5^a, 5^b and 5^c; the sections 5^a and 5^b being hinged together at 7, 7 and the sections 5^b and 5^c being hinged together at 8, 8. After the cover as a whole 70 has been raised and the sewing machine swung upwardly through the aperture in the table-top about its hinges 4^a, the sections 5^b and 5^c may be folded under the section 5^a, as shown in dotted lines, Fig. 2, and the front edge of the sewing machine bed-plate 4^b allowed to rest horizontally upon the ledge 9. The cover-sections 5^b, 5^c, are retained in folded position, by means of the spring clip 10 which is mounted on the 80 under side of the cover-section 5^a and is adapted to yieldingly grasp the inclined pin 11 mounted on the under side of the cover-section 5^b.

The invention comprises means for initially raising the cover 5 so that it may be 85 readily grasped by the operator. To this end there is mounted in a concealed position on the under side of the overhanging end of the top 1 a guide-bracket 12 having a 90 channelway 13 which receives the endwise 95 slideable push-rod or bar 14. The bar 14 is formed at its outer end with a head 15 carrying a positioning pin 16 for the outer end of the spring 17, the other end of which is seated in the aperture 18, Fig. 3, in the side-wall member 3 of the table. The bar 14 is formed at its other end with an upstanding 100 lip 19 having a cam edge or cover-lifting wedge 20 which normally is disposed entirely at one side of the space directly below the aperture in the table-top and hence does not offer any obstruction to the raising or lowering of the sewing machine. When the rod 14 is pushed inwardly the 105 cam-edge 20 engages the edge of the cover

and lifts the same, as shown in Fig. 4, so that such cover may be readily grasped by the operator and fully opened.

The present cover lifting device is entirely concealed, except for the head 15 which occupies an inconspicuous position beneath the top 1 and there are no finger holes, knobs, or the like, to mar the appearance of the table-top as a whole.

Having thus set forth the nature of the invention, what I claim herein is:—

1. A drop-head sewing machine table having a top wall and a receptacle below said top wall into which the sewing machine head may be lowered when not in use, said top wall having an aperture through which the sewing head may be raised to operative position, an in-set cover adapted to close said aperture flush with said top wall when the sewing machine head is housed in said receptacle, and a manually operated cover lifting element disposed at one side of the space directly below said cover when in in-

operative position and projectible across and below an edge of said cover into lifting engagement with the latter. 25

2. A drop-head sewing machine table having a top wall and a receptacle below said top wall into which the sewing machine head may be lowered when not in use, said top wall having an aperture through which the sewing head may be raised to operative position, an in-set cover adapted to close said aperture flush with said top wall when the sewing machine head is housed in said receptacle, and a slidably mounted rod disposed at one side of the space directly below said cover when in inoperative position, said rod having a cam at its inner end projectible across and below an edge of said 30 cover into lifting engagement with the latter. 35

In testimony whereof, I have signed my name to this specification.

PETER TAYLOR.
